UNITED STATES PATENT OFFICE.

WILLIAM G. WILSON, OF WEST NEW BRIGHTON, NEW YORK.

TRACK CONSTRUCTION.

Application filed May 31, 1924. Serial No. 717,101.

To all whom it may concern:

Be it known that I, WILLIAM G. WILSON, a citizen of the United States, residing at West New Brighton, Staten Island, in the 5 county of Richmond and State of New York, have invented new and useful Improvements in Track Constructions, of which the following is a specification.

This invention relates to improvements in 10 track construction and more particularly to track construction for street or surface railways.

The principal object of the invention is 15 the provision of a track which may be removed from the road bed without necessitating the taking up of the paving adjacent the entire rail, thus saving considerable time and labor when laying new rails for old.

20 Another object of the invention is to provide a rail of two parts, one part of which is stationarily mounted upon the supporting ties, and the other part over which the rolling stock passes being removably secured 25 to the stationary part and fastened thereto adjacent the ends of the part whereby only the road bed adjacent the ends of the rails is adapted to be removed to permit access 30 of the connections when desired to replace the part over which the rolling stock passes.

A further object of the invention is to 35 provide a track wherein the usual fish plates for connecting the meeting ends of the rails are dispensed with thereby saving a large amount of material, and time usually required for inserting bolts and applying nuts thereto.

With these and other objects in view, the 40 invention resides in certain novel construction and combination and arrangement of parts, the essential features of which are hereinafter fully described, are particularly pointed out in the appended claims, and are illustrated in the accompanying drawing, 45 in which:—

Figure 1 is a perspective view of my improved track construction.

Figure 2 is a side elevation.

Figure 3 is an enlarged detail side elevation showing how the sections are connected together.

Figure 4 is a vertical sectional view on the line 4—4 of Figure 2.

Referring more particularly to the drawing, the reference numeral 10 designates the track made up of lengths of my improved

50 rail 11. The rail 11 includes a stationary section 12 and a removable section 13 which are connected together adjacent their ends by attaching means 14.

The stationary section 12 comprises base flanges 15 which rest upon the usual ties 16, and from which rises a vertical flange 17. Tie rods 18 connect the stationary section of one rail with the stationary section of the 65 other rail as shown in Figures 1 and 2 of the drawing. The stationary section may be of any suitable length and the base flanges of the same are held to the ties 16 by means of the usual spikes 19 and tie rods. 70

75 Removable sections 13 comprise a head 20 adapted to overlie the flange 17 when in position thereon, and a depending flange 21 for co-action with the flange 17 to form the web of the rail. The section 13 is of the same 80 length as the section 12 so that the ends align with each other when in co-acting position. The meeting ends of one rail are staggered with relation to the meeting ends of the other adjacent rail to prevent undue 85 bumping at the joints as will be readily appreciated. The flange 21 of each removable section is cut-away as at 22 to permit the flange to pass over the brace rods 18. The attaching means 14 comprises a horizontal 90 slot 23 formed adjacent each end of the stationary section and a bayonet slot 24 formed in the flange 21 adjacent the ends of each removable section. A bolt 25 is slidable in the slot 23 and passes therethrough and when 95 applying the removable section to the stationary section, the bolt is moved to the inner end of the slot as shown in Figure 3, and the section 13 applied to permit the bolt to pass in the vertical portion of the bayonet slot 24. After the section 13 has been applied in this manner so that the horizontal slot of the bayonet slot is in register with the horizontal slot 23, the bolt is moved to 100 the outer end of the registering slots after which the nut 26, carried by the threaded shank of the bolt is screwed home to hold the parts in tight engagement with each other.

105 From the foregoing description, it is apparent that it is only necessary to remove the paving adjacent the ends of the rails in order to replace the sections 13 when they become worn by the rolling stock passing thereover. Furthermore, it is not necessary 110 to dispose of the entire rail as the life of the stationary section will be considerably longer

than the life of the removable section. It will also be noted that most of the weight of the rolling stock is carried by the flange 17 of the stationary member as the head of 5 the removable member rests directly upon the same. It will also be appreciated that it is not necessary to shift the co-acting sections longitudinally when connecting them but it is only necessary to slide the bolt as 10 previously explained.

While I have described what I deem to be the most desirable embodiment of my invention, it is obvious that many of the details may be varied without in any way departing 15 from the spirit of my invention, and I therefore do not limit myself to the exact details of construction herein set forth nor to anything less than the whole of my invention limited only by the appended claims. 20

What is claimed as new is:—

1. A rail comprising a stationary section having a vertical flange, a removable section having a head and a vertical flange depending therefrom, the head of said removable 25 section overlying the vertical flange of said stationary section, whereby to cause the load of the rolling stock passing over said head to be taken up by said stationary section, and means for detachably connecting said 30 sections together, said means including registering horizontal slots formed at the ends of said sections, the horizontal slots in said

removable section communicating with vertical slots, and securing elements slideable in said horizontal slots. 35

2. A rail comprising a pair of co-acting sections, one of said sections being provided with a horizontal slot adjacent each end thereof, the other of said sections being formed with a bayonet slot adjacent each 40 end, a securing element extending through each horizontal slot and adapted to be moved to one end of the slot to permit the same to enter the bayonet slot when the parts are brought into co-acting position, said element adapted to be moved to the opposite end of the slot when the sections are in co-acting position to lock the same. 45

3. A rail comprising a pair of co-acting sections, one of said sections adapted to be secured to the ties of a road bed, securing elements carried adjacent the ends of said section and slideable thereon, the other of said sections adapted to be dropped vertically beside said first section, slots formed adjacent the ends of said last section for receiving the securing elements when the said sections are in co-acting engagement, after which said securing elements are moved to a locking position. 50 55

In testimony whereof I have affixed my signature.

WILLIAM G. WILSON.
